UNITED STATES PATENT OFFICE.

PARLEY A. DAILEY, OF NEW YORK, N. Y.

FIGURED FABRIC.

SPECIFICATION forming part of Letters Patent No. 358,146, dated February 22, 1887.

Application filed August 6, 1886. Serial No. 210,184. (No model.)

To all whom it may concern:

Be it known that I, PARLEY A. DAILEY, of the city and State of New York, have invented an Improvement in Figured Fabrics, of which 5 the following is a specification.

This invention is for ornamenting the surface of woolen and other fabrics with figures, designs, or other patterns, the figure being raised and of a different color from the foundation or background, or the reverse, thereby producing a beautiful finish to the goods, and by my improvement the cost of manufacture is comparatively slight.

In the drawings I have illustrated by sectional views, on a magnified scale, the successive steps of my improvement, in which—

Figure 1 shows the first stage of the fabric; Fig. 2, the second stage of the fabric, and Fig. 3 is a section of the complete fabric.

10 The foundation of the fabric may be woven, felted, or knitted, and it is preferably of woolen or other material having sufficient felting properties for the operations hereinafter described. Upon this foundation A, Fig. 1, I apply a sheet 15 of wool or other fibrous material, as at B, and cause the two to adhere in any desired manner—such, for instance, as by a preliminary felting or fulling operation, or by hardening the two together. This sheet B is of a different 20 color to the foundation fabric, so that the figure, when produced by this layer B of fibrous material, may contrast in color with the background. The fabric is now passed through 25 between embossing-rollers, which press down and indent the design, pattern, or figure, and this embossing should be in the presence of sufficient heat to render the embossing permanent. The embossed fabric is represented 30 in the section, Fig. 2. The fabric is now passed 35 through a shearing-machine, and the portion of the layer B which is not indented removed, so that the color of the foundation fabric is visible. This develops the pattern, because the 40 pattern itself is not sheared, having been indented. In this condition the goods may be put upon the market; but usually it is preferable to submit the same to a steaming, fulling, or felting operation, which more firmly unites 45 the fibrous layer forming the pattern, and renders the fabric uniformly pliable, and the 50 fibrous materials forming the design or pattern

now assume a raised condition, as indicated in Fig. 3. When the figure of the pattern is produced by the foundation color, then the background is indented and the figure sheared off, 55 and the surface color becomes the background.

Fabrics furnished in this manner possess great beauty in consequence of the figures being of a different color from the ground-work or body, and in addition to this, when the figure is raised, the ornamental appearance is increased because of the prominence of the figure.

This fabric may be produced by weaving a surface fabric of a different color upon the foundation fabric, or by felting upon the foundation fabric the layer of surface fibers, the felting being done by gangs of reciprocating needles. In all cases the embossing or indenting and the shearing operations are made use of.

I am aware that velvets and plashes have 70 been embossed, and in some instances embossed fabrics have been sheared. I therefore do not claim either operation; and ornaments have been attached by sewing either before or after being cut out.

75 It will be apparent that when figures are cut out and applied to the surface of a fabric and united thereto, as has before been done, it is impossible to repeat the figures with absolute accuracy. With my improvement the 80 embossing is accurate. The figures are always in the proper relative positions, and after the shearing and raising operations have been performed the edges of the raised figures or designs are beveled, as illustrated in the drawings, and a fabric made according to my methods is easily distinguished from pre-existing 85 fabrics by these peculiarities.

I claim as my invention—

1. The method herein specified of producing 90 figures or designs upon fabrics, consisting in applying to the foundation fabric a layer of fibrous material of a different color to the foundation fabric, felting the two materials together, indenting the pattern or figure by an 95 embossing operation, and removing the portion of the layer that is not indented by a shearing operation, substantially as set forth.

2. The method herein specified of producing 100 figures or designs upon fabrics, consisting in uniting to the foundation fabric a layer of fibrous material of a different color from the

foundation fabric, indenting the pattern or figure by an embossing operation, and removing the portion of the layer that is not indented by a shearing operation, and fulling or felting the fabric, substantially as set forth.

3. The figured fabric having the pattern upon its surface composed of a layer of fibers of different color from the foundation fabric, and the entire pattern substantially integral with

the foundation fabric, and the edges of the 10 raised portion beveled to the surface of the foundation, substantially as set forth.

Signed by me this 4th day of August, 1886.

P. A. DAILEY.
